UNITED STATES PATENT OFFICE,

CHARLES G. MITCHELL, OF MONTREAL, QUEBEC, CANADA

ADJUSTABLE FRAME.

Application filed August 19, 1927. Serial No. 214,144.

This invention relates to new and useful improvements in frames for grilles, switch boxes, wall cabinets and the like which are adapted to lie flush with a wall face.

5 The object of the invention is to provide a frame which will be quickly and easily adjusted to suit the wall face.

Another object is to provide an adjustable frame which will be simple in construction and which will be easily and economically manufactured.

According to my invention, I provide a flanged frame through which screws are provided which engage with threaded apertures formed in a flange formed in the box or cabinet to which the frame is attached. Locking nuts are provided to prevent longitudinal movement of the screws in the frame and to lock the screws in any adjusted position. The frame is provided with a ridge into which the cover for the opening is placed so that the frame and the cover or grille is made flush with the wall face.

In the drawings which illustrate my invention:

Figure 1 is a perspective view of a frame with a hinged cover.

Figure 2 is a perspective view of the back of the frame shown in Figure 1.

30 Figure 3 is a sectional side elevation of part of the frame and a grille cover showing the method of attaching the frame to a flange.

Figure 4 is a sectional side elevation of a frame and cover showing one type of connection between them.

Figure 5 is a perspective view of a frame and cover showing another method of attaching them together.

40. Figure 6 is a perspective view of a frame showing a still further method of attaching a cover or grille to a frame.

Referring more particularly to the drawings, 11 designates a wall which is provided with an aperture or recess 12 within which is placed a metallic air duct or box 13 having an outwardly turned flange 14. The box or duct is preferably made of thin metal and the flange is formed by bending the metal outwardly and also bending the metal to form a plurality of layers as shown in Figure 3. The flange is provided with threaded apertures 15 to engage with the threads of the adjusting screws 16 which pass through the flange 17 of a frame 18, the legs 19 of which project into and frictionally engage

with the walls 20 of the box or duct. The legs 19 are preferably formed at right angles to the flange. The edge of the flange is provided with an outwardly turned rib or beading 21. The height of the beading is preferably such that when a cover or grille is placed on the flange, the exposed edge of the flange will be flush with the exposed face of the said cover or door. In Figure 3 a grille is shown and the manner of attaching said grille is shown in Figure 6. Apertures 22 are formed in the grille to receive the countersunk heads of the set screws 23, the threads of which engage with threaded apertures 24 formed in the frame flange. The heads of the adjusting screws are covered by the grille. In Figure 5 the frame is provided with a cover 25 connected to the frame by means of the hinges 26, at one edge. Each hinge is of the triple side type, one side 27 secured to the frame, another side connected to the cover and the third or middle side pivotally connected between the other two sides. The flange of the frame is provided with slots 28 to allow a certain amount of flexibility between the frame and the cover during the opening of same. The cover is held in the closed position by means of the sliding bolt 29 which engages with an aperture 30 formed in the adjacent leg of the frame. In Figure 4 the cover is attached to the frame by means of the bent bars 31 which are slidably attached to the frame and are each provided with a head 32 to hold the cover to the frame. Each adjusting screw is provided with a lock nut 33 which frictionally engages with the underside of the frame and prevents movement of the screw with respect to its longitudinal axis. The nuts also form a locking means to hold the frame in any adjusted position with respect to the flange of the box or duct.

In operation, the flange of the box or duct, or the like, is positioned against the solid concrete or brick portion of the wall. The frame is then placed in position with the legs frictionally engaging with the inner wall of the box. The adjusting screws are rotated and are adapted to move the frame toward or away from the flange of the duct or box. When moving the frame the nuts on the screws act as collars and when the frame is at the desired distance from the box flange the nuts are turned to lock the frame in position. The heads of the adjusting screws are protected by the cover or grille which may 100 105 110

be attached to the frame by hinges or by screws.

The device is very easily manufactured and provides a simple means for aligning a plurality of boxes so that when the plaster 34 is placed in position no part of the frame or cover projects beyond the wall face 35.

Having thus described my invention, what I claim is:—

- 10 1. In a device of the class described, a frame having a flange, a box having a flanged end, adjusting screws rotatably held in the frame flange and adapted to engage with threaded apertures in the box flange and lock 15 nuts mounted on the screws and adapted to engage with the frame flange to hold the flange of the frame a predetermined distance from that of the box.
- 20 2. In a device of the class described, a frame having an outwardly turned flange, a box frictionally engaging with the frame and also provided with an outwardly turned flange, adjusting screws rotatably held in the frame flange, and adapted to engage with threaded apertures in the box flange, lock nuts 25 to prevent movement of the screws in their longitudinal direction with respect to the flange and to lock the screws against rotation when so desired.
- 30 3. In a device of the class described, a frame having a flange, a box frictionally engaging with the frame and provided with a flange, adjusting screws rotatably mounted in the frame and adapted to engage with 35 threaded apertures in the box flange, lock nuts mounted on the screws and adapted to frictionally engage with the flange of the frame to prevent movement of the screws when in any adjusted position and means secured to 40 the flange of the frame and covering the heads of the adjusting screws.
4. In a device of the class described, a

frame, having an outwardly turned flange, a box secured to a wall and also provided with an outwardly turned flange, countersunk adjusting screws rotatably held in the frame flange by lock nuts which when turned lock the screws against rotation, said screws being adapted to engage with threaded apertures formed in the box flange, and a cover secured 50 to the frame flange and adapted to cover the heads of the adjusting screws, said cover being adapted to lie flush with a beading formed around the edge of the frame flange.

5. In a device of the class described, a frame having an outwardly turned flange secured to a wall, adjusting screws rotatably held in the frame flange and adapted to engage with threaded apertures in the flange in the wall, said screws being countersunk in 55 the frame flange, a cover hingedly attached to the frame flange and adapted to cover the heads of the adjusting screws, means to lock the cover in the closed position, said cover being sunk into the flange and surrounded by 60 a beading formed thereon, said beading being adapted to lie flush with the cover in the closed position.

6. A device of the character described comprising a frame, a box in which the frame is 70 slidably fitted, adjusting screws passing through registering openings of the frame and box and having threaded engagement with the openings of the box and means carried by the adjusting screws and engaging the frame to prevent longitudinal movement of the screws relative to the frame whereby the frame is caused to travel with the screws as the latter are threaded inwardly or outwardly with reference to the box.

In witness whereof, I have hereunto set my hand.

CHARLES G. MITCHELL.
